UNITED STATES PATENT OFFICE.

EDWARD J. MOORE, OF PHILADELPHIA, PENNSYLVANIA.

STEAM-BOILER.

SPECIFICATION forming part of Letters Patent No. 487,075, dated November 29, 1892.

Application filed September 26, 1891. Serial No. 406,910. (No model.)

To all whom it may concern:

Be it known that I, EDWARD J. MOORE, a citizen of the United States, and a resident of Philadelphia, Pennsylvania, have invented 5 certain Improvements in Steam-Boilers, of which the following is a specification.

My invention relates to the construction of an improved sectional steam-boiler having steam and water drums and circulating-tubes.

10 The object of my invention is to improve the construction of several minor parts of the boiler, as described hereinafter, reference being had to the accompanying drawings, in which—

15 Figure 1 is a longitudinal section of my improved steam-boiler. Fig. 2 is a transverse section on the line 1 2, Fig. 1. Fig. 3 is a transverse section on the line 3 4, Fig. 1. Fig. 4 is a sectional view of one of the header-sections. Fig. 5 is a section on the line 5 6, Fig. 4. Fig. 6 is a perspective view of one of the plates adapted to the space between the two sections of a header. Fig. 7 is an enlarged detail of the manifold shown in Fig. 1. Fig. 25 8 is a section on the line 7 8, Fig. 7. Fig. 9 is a sectional view illustrating the construction of a cap for inclosing the hand-hole openings. Fig. 10 is a view of a modification illustrating a different construction of steam and water drum, and Figs. 11 and 12 are views of modifications of the header-section.

30 Referring to Figs. 1, 2, and 3, A is the brick-work of the boiler; B, the combustion-chamber; b, the grate-bars; b', the ash-pit opening, and b² the stoke-hole.

35 D are inclined circulating-tubes connected at their forward ends to the header M and are attached at their rear to the rear header N. These headers are in turn connected to the 40 water drum or drums S, the forward header M being connected to said drum by nipples s and the rear header connected to the drum by tubes s'.

45 Between the drums S, as clearly shown in Figs. 2 and 3, are tubes S', connected to manifolds S², shaped to snugly fit the drums, so that the least possible room is taken up by the drums and tubes. Above this series of drums and tubes are a series of steam drums 50 and tubes, described hereinafter. The deflecting-plate a extends from the front header M to an arch A', which supports a frame a², on

which the plate a is mounted, so that the products of combustion will be directed under the arch A' to the second combustion-chamber B', in which the majority of the tubes are situated. The two lower rows of tubes in the present instance are within the primary combustion-chamber B, being separated from the other tubes by the plate a. The deflecting- 55 plate a' is mounted above the inclined tubes, forming a partition between the combustion-chamber B' and chamber B².

It will be noticed in referring to Fig. 1 that the front header is made up of a series of sections m and that there is a space between each section for the insertion of a cleaning-tool. Each section is connected to the adjoining one by nipples c, and the space between each section is filled by a plate C, Fig. 6, which is made in the present instance to fit around the said nipples, being cut out at c'. The plate is also provided with handles c², into which hooks can be inserted to remove the plate when it is required to get at the 65 opening. The deflecting-plate a is so arranged that its upper surface is on a line with the upper edge of the lower section of the front header. When the plate C is removed, a tool can be inserted to clean the surface of 70 said plate, after which the plate C can again be placed in position, preventing the products of combustion passing through the opening 75 between the sections. The rear header N is constructed similar to the forward header, 75 and is also provided with filling-plates C, so that access may be had to the exterior 80 surface of the tubes. The upper deflecting-plate a' is on a line with the upper surface of the rear header, and between the rear header and 85 the wall of the furnace is a plate a³, in which are holes a⁴, having caps a⁵. By turning these caps a tool can be inserted into any one of the 90 holes and the upper surface of the plate a' cleaned.

95 The rear wall of the furnace is preferably provided with a doorway and door, so that access may be had to the rear header.

Opposite each tube D in the front and rear headers are hand-holes covered by caps of 100 the form shown in Fig. 5, the details of which will be described hereinafter. On removing these caps the interior of the tubes can be readily cleansed.

The second combustion-chamber B' is formed by the two deflecting-plates a a' , while the third combustion-chamber B^2 is formed by the deflecting-plate a' and the drums, the products of combustion passing from this chamber to the flue B^3 .

Each section of the front and rear header is cast, as shown in Figs. 4 and 5, having tube-openings, hand-hole openings, and nipple-openings, and in order to stiffen the structure internal ribs m' are formed on the front and rear faces of the section. I have shown these ribs in Figs. 4 and 5 merely as straight ribs broken at intervals to allow for the free flow of water; but in Fig. 11 I have shown the ribs diagonal. The form and character of the ribs depend upon the construction of the boiler.

It will be noticed that the water-drum S is made in the form of a single tube provided with a head at each end, the head, however, having a hand-hole opening and in some cases a manhole-opening, which is covered by a suitable cap of the construction described hereinafter. This drum can be made of any suitable material adapted for the purpose; but I prefer where practicable to make it of aluminium alloy, which is described and claimed in an application filed by me of even date herewith.

By making the drums of steam-boiler seamless I am enabled to make a boiler to withstand high pressure and which is not so liable to burn out as riveted boilers, which are weakened by the rivet-holes, and the rivets, moreover, are liable to soften, owing to the thickness of metal on the rivet-line, and the boiler can be kept clean, as there are no ledges to entrap sediment. The tube is expanded near its front end, so as to form an enlargement s' , to which the front header M is coupled by the nipples s , the rear portion of the drum being also formed to receive the tube s' and the nipple e , which forms a connection between the drum and the steam-manifold, described hereinafter. The water-manifolds S^2 are preferably cast and are connected together, as above described, by tubes S' and are similar in construction to the steam-manifold shown in Fig. 1. The lower portions of the water-manifold are so shaped that they will be on the same line as the inclined upper portion of the front header, so that they can be readily nipped thereto by the nipples s , as shown clearly in Fig. 2. The products of combustion as they pass over the deflecting-plate a' come into contact with these two drums and tubes.

I have shown in Fig. 2 three water-drums arranged in line, separated by two manifolds and tubes, and arranged above these water-drums are three steam-drums and one set of tubes and manifold.

Two steam-drums I I are arranged in line with the tubes J J and the manifold J' , and directly above the manifold is a third steam-drum I' . These steam-drums and manifolds

are connected to the water-drum and water-manifold at the rear end of the boiler only, as shown in Fig. 3. The central drum S is connected to the manifold J' by a nipple. The nipples connect the manifolds S^2 with the drums I I . The outer drums S are connected to the drums I by pipes i i , (shown by dotted lines in Fig. 3 and full lines in Fig. 1,) so that steam as it is formed passes up the nipples and tubes to the steam drum and manifolds. The steam-drum I' is connected at both ends to both steam-drums I I by pipes i' and to the manifold by nipples i^2 and communicates with the steam-supply pipe I^2 at its forward end.

It will be seen that the structure above described is what may be termed a "built-up" structure, having independent drums and independent sections composed of manifolds and tubes, so that the boiler can be built up in any desired form and the steam and water space can be increased or diminished, as desired. The form herein shown need not be adhered to, as in some instances the drums, tubes, and manifolds may be arranged as shown in Fig. 10, which illustrates a section on the line 1 2, Fig. 1, of the upper portion of the boiler only. In this instance instead of arranging the drums and sections in conical form they are arranged in two rows. The view illustrates the front portion of the drums and manifolds. The nipples e , forming communications between the water and steam drums and manifolds, are shown in the distance, and the steam-drums and manifolds are connected to a single steam-receiver I^3 through passages i^3 .

The manifolds are preferably cast as shown in Figs. 7 and 8 and have tube-openings at the rear and nipple-openings and hand-hole openings. These hand-hole openings are in the front plate in line with the tube-openings and are capped, as shown in Fig. 7. These caps F , as clearly shown in Fig. 9, are seated to the ground face f and are of such diameter and thickness that when used as caps for the drum (either water or steam drum) they will yield under certain extreme pressures, the pressure forcing the cap off its seat rather than explode the boiler, thus allowing the steam to escape. This cap is held in place by a perforated plate F' , which need not fit its seat snugly. Steam enters the space f' between the plate and cap through the perforations in the plate F' . Passing through both the plate and cap is a bolt F^2 , having a head on the inside and having a screw-threaded end, to which is adapted the box-nut f^2 . The face of this nut is ground to its seat on the cap F , so that the joint will be perfectly steam-tight. The same construction of cap is found in Fig. 7, only on a smaller scale.

In Figs. 4 and 5, which illustrate one of the header-sections, I have shown elongated openings in the front plate opposite the tubes D . The openings are of such a width that

two tubes are accessible through one opening. Thus more room is allowed for working tools in attaching the tubes to the header and in repairing. An elongated cap F^3 covers the opening, as shown in said figures, and on the inside is a plate F^4 of the same construction as the plate F' , Fig. 9. A single central bolt F^2 attaches the plate and cap to the header, and the cap is of such thickness and sheet that it will yield to excessive pressure.

In order that the ends of the drums, as well as the manifolds, may be accessible at all times, I form a partition-wall P directly back of each manifold, as shown in Fig. 1. This partition I preferably make of metal, having suitable openings for the passage of the drums and tubes, and line its face which is exposed to the products of combustion with fire-brick or analogous material p . Thus while the circulation through the several tubes and drums is not interrupted, the manifold and drums can be examined at all times by simply opening suitable doors in the front and rear of the furnace.

In order to prevent pitting of the several metal parts that are not made of aluminium or an alloy thereof, I prefer a wash of aluminium and coat the parts exposed, thus preventing to a great degree the corrosion and pitting which is so injurious to steam-boilers. I also wash the small parts of the boiler which are exposed to moisture with the same material for the same purpose.

In order to economize in the manufacture of boilers of different widths, I preferably make the pattern for the header-section for a narrow boiler and merely add a section to one or both ends of the header-pattern, as shown in Fig. 12, and perforate the end m^2 , so that the water will circulate through the addition, the end m^2 becoming a stay to strengthen the header.

I claim as my invention—

1. The combination, in a steam-boiler, of the inclined tubes and front and rear headers with a series of water-drums and a series of water-tubes in line with the water-drums, manifolds at each end communicating with the water-tubes and independent of the water-drums, substantially as described.

2. The combination, in a steam-boiler, of the inclined tubes, the front and rear headers, a series of water-drums separated by a series of water-tubes, and manifolds therefor, said drums and manifolds being connected independently with the front and rear headers, substantially as described.

3. The combination of the inclined tubes, the front and rear headers, a series of water-drums, a series of water-tubes, the front and rear manifolds therefor, nipples connecting the drums and manifolds with the front header, and tubes connecting the rear portions of the drums and the rear manifolds to the rear header with a steam-receiver mounted above the drums and tubes and connected to the

rear portions of the drums and to the rear manifolds, substantially as described.

4. The combination, in a steam-boiler, of the inclined tubes and front and rear headers, the water drums and tubes, manifolds for said tubes, a series of steam-drums mounted above said water drums and tubes, steam-tubes and steam-manifolds for said tubes, the steam drums and manifolds being connected at the rear of the boiler with the water-tubes and manifolds, substantially as described.

5. The combination, in a steam-boiler of a type substantially as described, of a series of water-drums, water-tubes, and manifolds, the steam drums and manifolds mounted above the water drums and manifolds, and nipples and pipes connecting the steam drums and manifolds with the water drums and manifolds at the rear end only, substantially as set forth.

6. The combination, in a steam-boiler, of the inclined tubes, the front and rear headers, the three water-drums arranged in line, the two sets of water-tubes, front and rear manifolds for each set, separating the drums, steam-drums mounted directly above the water-manifolds, and steam tubes and manifolds mounted directly above the central water-drum, and a steam-drum mounted above the steam tubes and manifolds and connected with the manifolds and with the two steam-drums, the said two steam-drums and rear manifolds being connected to the water drums and manifolds at the rear of the boiler, substantially as described.

7. The combination, in a steam-boiler, of the inclined tubes, front and rear headers, and the water and steam drums with front and rear partitions P , arranged back of the nipping of the drums, so that the heads of the drums are exposed for examination at all times, substantially as described.

8. The combination of the inclined tubes, the front and rear headers, the steam-drums and steam-tubes, the water-drums and water-tubes, manifolds for the several tubes, partitions P , arranged at the back of each manifold, and linings for said partitions, said partitions having openings for the drums and tubes, substantially as described.

9. The combination, in a steam-boiler, of the inclined tubes, the front and rear sectional headers, spaces between each section of the headers, and nipples securing the sections together with filling-plates adapted to fit in the spaces between the sections, substantially as described.

10. The combination, in a steam-boiler, of the sectional headers, nipples securing the said sections together and forming a space between each section for the insertion of a cleaning-tool, and filling-plates C , recessed at c' for the nipples and provided with handles by which they can be removed, substantially as described.

11. The combination of the inclined tubes, the front and rear headers, a drum connected

- with the front and rear headers, said headers being sectional, spaces between each section, and a deflecting-plate a , extending from the front header, the upper surface of said plate being on a line with one of the spaces and with a filling-plate, whereby on the removal of the filling-plate a tool can be introduced to clear the upper surface of the deflecting-plate, substantially as described.
- 10 12. A horizontal steam or water drum for steam-boilers, made of a seamless tube contracted at each end to form heads and expanded at the coupling-points, substantially as specified.
- 15 13. The combination of the section of a steam-boiler, an opening therein, a cap for said opening, adapted to a ground seat on the outside of said section, a plate on the inside of the section, and perforations in said plate for the passage of steam to the space between the cap and plate, with a securing-bolt confining the plate and cap to the section, substantially as set forth.
14. The combination of the rectangular header-section of a steam-boiler with an extension-section cast on one or both ends of the header-section and coupled to the circulating-tubes, the end plate of the header-section being perforated to permit circulation, substantially as set forth.
- In testimony whereof I have signed my name to this specification in the presence of two subscribing witnesses.

EDWARD J. MOORE.
